Thermoid Company, Trenton, N. J., a corpora-
tion of Delaware

Original application October 13, 1936, Serial No.
105,428. Divided and this application Novem-
ber 29, 1937, Serial No. 177,132

3 Claims. (Cl. 139—104)

This invention relates to looms, and more particularly to a loom capable of weaving pile carpet, double, i. e., weaving the base fabrics for two independent carpets in superposed relation to 5 each other with pile-forming threads extending from one base fabric to the other base fabric during weaving; and wherein the pile warps are subsequently cut in a plane intermediate the two base fabrics, to split the two carpets apart and 10 thereby produce a cut pile face on each carpet.

The present application is a division of copending application, Serial No. 105,428, filed October 13, 1936.

The present invention more especially concerns 15 an improved form of warp feeding or tensioning mechanism. The cooperation and coordination mechanism of the present invention with other new and normal elements of the loom will be fully disclosed hereinafter, reference being had to the 20 accompanying drawings, of which:

Fig. 1 is a longitudinal sectional elevation, in more or less diagrammatic form, illustrating the mechanism of the present invention applied to a loom of the type noted and showing the lay of the 25 loom in the beat-up or front-center position with the reed immediately adjacent the fell of the carpet;

Fig. 2 is an enlarged fragmentary view illustrating the lay in the same position as in Fig. 1;

Fig. 3 is a still greater enlargement at and 30 immediately surrounding the fell of the fabric being woven, with the lay in the beat-up position shown in Figs. 1 and 2 and the carpet in longitudinal section;

Fig. 4 is a side elevation partly in section of the 35 warp-tensioning mechanism forming a part of the present invention;

Fig. 5 is a sectional plan view taken on the line 5—5, Fig. 4;

Fig. 6 is a front elevation of the warp-tensioning 40 mechanism shown in Fig. 4; and

Fig. 7 is a vertical sectional elevation taken on the line 7—7, Fig. 6.

A loom of the type above noted normally comprises a breast beam 1. The loom also includes a lay 2 which is pivoted at 3 to the frame of the loom. The lay 2 is provided with the usual reed 4. The lay 2 is normally rocked about the pivot 3 by a crank shaft (not shown) connected to the 45 lay by the usual form of connecting rod. When the reed is in the beat-up or "front-center" position shown in Figs. 1 and 2 the crank and connecting link are fully extended with the axis of the pivot between the connecting link and the lay, 50 the axis of the pivot between the connecting link

and the crank, and the axis of the crank shaft itself all lying in a straight line. As the crank shaft revolves to the extent of 180° the lay 2 is moved thereby to the "back-center" position, wherein the above noted axes are again in line, 5 with a line extending from the axis at one end of the connecting link to the axis at the opposite end thereof lying across the axis of the crank shaft.

The loom also normally includes a series of 10 heddle frames illustrated at 5, 6, 7, 8, 9 and 10 respectively. These heddle frames are normally raised and lowered in predetermined relationship to each other while the lay is in the front-center position, in order to provide an open warp shed 15 for the reception of the filling shuttle which is shot transversely across the loom when the lay moves again to the back-center position above noted.

The raising and lowering of the heddle frames 20 5 to 10 inclusive, in predetermined relationship to each other, is normally produced by a series of cams individual to the heddle frames and mounted on a common shaft which is driven at a predetermined speed with respect to the oscillations 25 of the lay 2. This mechanism is common in the type of loom noted and is well known to those familiar with the weaving art and for that reason has not been illustrated in the present instance.

The loom also includes the usual whip roll 11 30 and warp guide roll 12 about which the warp threads pass in normally extending from a warp beam at the rear of the loom to and through the heddles of the frames 5 to 10 inclusive and through the dents in the lay reed 4, to the fell of 35 the fabric at the front of the loom.

On the front upper corner of the breast beam 1 and extending transversely of the loom, and normally mounted for rotation in suitable bearings 40 carried by the breast beam 1 or by the main frame of the loom, is a guide roll 13 over which the finished fabric passes.

The loom also includes the usual form of pin roll 16 and guide roll 17 around which the fabric also 45 passes. The fabric is taken up intermittently, i. e. for each beat-up motion of the lay or for each pick, by the pin roll 16, which maintains the fabric and the warp threads under tension. The rolls 16 and 17 are suitably mounted for rotation 50 in the side frames 14 of the loom.

The loom is also provided with fabric guide rolls 18 and 19 and a mandrel 20 on which the completed fabric is wound, said mandrel being 55 driven in any suitable manner to wind the fabric

step by step as it is advanced from the fell by the intermittent movements of the pin roll 16.

In the present instance, the warp beam is supported by a suitable rack of any well known type 5 and upon which is mounted a series of cones, bobbins, spools or other yarn packages 21, 21 containing warp threads *a*, which, as will be more fully disclosed hereinafter, constitute the warp threads for the lowermost of the two base fabrics. 10 The rack also supports a series of yarn packages 22 which supply threads *b*, which constitute the warp threads for the uppermost base fabric. Also carried by the rack is a plurality of yarn packages 23 which supply the pile warps *c*. The pile warps 15 *c* are adapted to be interwoven with each of the base fabrics and to extend from one to the other thereof in a manner hereinafter described more fully.

The warps *a*, *b* and *c* respectively pass through 20 guide or separating plates 24, 25 and 26 from the bobbins 21, 22 and 23 respectively to guide rolls 27, 28 and 29. The guide plates 24, 25 and 26 are provided with suitable relatively spaced openings or perforations 30 through which the 25 warp threads *a*, *b* and *c* pass and by which the threads of each group thereof are retained in predetermined relation to each other for presentation to the guide rolls 27, 28 and 29. From the guide rolls 27, 28 and 29 the groups of warp 30 threads *a*, *b* and *c* pass around tensioning rolls 31, 32 and 33 respectively.

From the tensioning roll 31 the warp threads *a* pass to and around a guide roll 34 and in so doing said warp threads pass through and between the threads *a*, where said group of threads 35 are passing from the guide plate 24 to the guide roll 27, as indicated at *x*¹ in Fig. 1. The threads *a* pass from the guide roll 34 to and over a fixed supporting bar 35, which is disposed adjacent 40 and parallel to the guide roll 12.

The bar 35 is provided with a series of vertical pins 36 which are spaced apart longitudinally of the support 35 which latter extends transversely of the loom and is supported in any suitable manner by the main frames 14 of the loom.

The warp threads *b* pass from the tensioning roll 32 through that portion of the group of threads *b* which is stretched between the guide roll 28 and the tensioning roll 32, as indicated 50 at *x*², said threads *b* then passing to the support 35 and between the guide pins 36 thereon, which maintains the threads *b* in predetermined relation to the thread *a* for delivery to the guide roll 12 and whip roll 11 of the loom.

The pile warp threads *c* pass from the tensioning roll 33 through the group *c* where said group extends from the guide roll 29 to the tension roll 33, as indicated at *x*³ in Fig. 1. The pile warp threads *c* pass from the intersecting point *x*³ directly to and through heddle eyes 37. The heddle eyes 37 are carried by heddle wires 38 which in turn are carried by the heddle frame 6, in the present instance, said threads passing from the heddle eyes 37 to the fell *x* of the fabric, 60 as illustrated in Fig. 3.

From the whip roll 11 the warp threads *a* and *b* respectively pass under and over a separating bar 39, then over and under a second separating bar 40. The two groups of threads cross each other and pass through each other between the bars 39 and 40 at the intersecting points *x*⁴ as 70 illustrated in Fig. 1. From the bar 40 the warp threads *a* pass to and through heddle eyes 41 and 42 carried by heddle wires 43 and 44 respectively. The wires 43 and 44 are carried by the

75
heddle frames 9 and 10 respectively. The warp threads *a* pass from said heddle eyes 41 and 42 through the dents in the reed 4 of the lay 2, to the lower base fabrics A at the fell X.

The warp threads *b* pass from the separating 5 bar 40 to heddle eyes 45 and 46 which are carried by heddle wires 47 and 48. These heddle wires are carried by the heddle frames 7 and 8 respectively. The warp threads *b* pass from the heddle eyes 45 and 46 through the dents in the lay reed 10 4 to the upper base fabric B at the fell X.

The fabrics A and B are maintained in vertically spaced relation to each other by separating blades 50, said blades being arranged in laterally spaced relation to each other and disposed horizontally between a rearwardly projecting lip 51 of the breast beam 1 and a transversely extending bar 52 which is arranged above and in spaced relation to the upper surface of the breast beam to provide a guideway 53 for 20 the separating blades 50.

The blades 50, 50 extend longitudinally of the loom and are arranged to move longitudinally through the guideway 53, with the fabrics A, B, during the beat-up movement of the lay to the 25 front-center position and to be retracted slightly in the opposite direction during the movement of the lay to the back-center position, as will be more fully disclosed hereinafter.

The separating blades are of a width corresponding to twice the height of the pile required on each of the fabrics A and B, said separating blades being arranged in vertical planes and spaced laterally to provide spaces therebetween through which the pile warps *c* pass in extending from the lower base fabric A to the upper base fabric B and vice versa to produce the interconnecting pile area C between said fabrics A and B.

The groups of body or ground warp threads 40 *a* and *b* are sub-divided into two substantially equal series which as the heddle frames rise and fall during the course of the weaving operation are alternately raised and lowered to produce an open warp shed D through which the weft or filling threads *a*¹, *b*¹ of the fabrics A and B are alternately carried by a separate shuttle propelled through successive warp sheds by the usual picking mechanism of the loom.

The heddle cams are so arranged that a warp 50 shed is first produced by raising all of the warp threads *b* and one-half of the warp threads *a*, the other half of the warp threads *a* and the pile warps *c* being lowered, and producing the warp shed for receiving one of the weft or filling threads *a*¹ of the lower fabric A.

After insertion of the filling or weft threads *a*¹ the warp shed changes. All of the warp threads *a* and one-half of the warp threads *b* are lowered and one-half of the warp threads *b* and all of 60 the pile warps *c* are raised to produce the next open warp shed D², shown in Fig. 3, for the reception of one of the wefts *b*¹ of the upper fabric B.

After the insertion of each weft *a*¹ or *b*¹, as the case may be, the lay 2 beats up in the usual 65 manner, the blades or wires constituting the reed 4 engaging the last inserted weft, in the manner illustrated in Fig. 3, and holding it in position at the fell X as the heddle frames change positions to produce the next warp shed for the introduction of the next filling thread *a*¹ or *b*¹, as the case may be.

It will be noted that all of the weft threads *a*¹ are inserted below the spacing blades 58 and all of the filling threads or weft threads *b*¹ of the 75

upper fabric B are inserted above the spacing blades 50, and in order to accomplish this procedure with the limited rise and fall of the heddle frames available in the loom of the type noted each of the spacing blades 50 is provided with a relatively movable section 55.

The movable sections 55, 55 of the spacing blades 50, 50 are pivotally connected at 56, 56 to the back ends 57, 57 of the spacing blade 50, 50 respectively and rise and fall with and in predetermined relation to the warp threads a, b and c.

As shown in Fig. 3, the two base fabrics A and B, after being woven at the fell X, ride longitudinally along the lower and upper edges 59 and 58 respectively of the blades 50. The two base fabrics A and B are separated by the vertical width of the blades 50, which determines the length of the pile tufts to be formed by the pile threads c in each case as the threads c, c pass across the pile region C between the two fabrics. The double pile fabric composed of the two base fabrics and interconnecting pile threads rides off the forward ends 60 of the spacing blades 50 as 25 the pin roll 16 takes off the fabric, step by step, with the beat-up movements of the lay 2.

The forward ends 61 of the movable sections 55 of the blades 50 are each provided with an opening 62. A tongue 65 projecting laterally from the rear end 57 of each of the blades 50 passes through the opening 62 formed in the movable section 55 of the blade 50. The tongues 65 are formed integrally with the rear ends 57 of the blades 50 and, after passing through the openings 62 in the movable sections 55, are bent forwardly and lie substantially parallel to the blades 50.

The free ends 61 of the tongue portions 66 project forwardly beyond and terminate in front of the joints 56 formed between the two relatively movable blade sections 50 and 55, so that as the double fabric moves along the blades 50 in the manner above noted and passes off the ends 60 thereof the pile threads c within the pile region 45 C will slide freely past and over the free ends 61 of the blade tongues 66.

The rear end of the movable section 55 of each spacing blade 50 is pivotally connected at 71 to and between a pair of heddle blades 72. The control blades 72 extend vertically and are disposed in laterally spaced relation to each other within the plane of and suitably connected to the heddle frame 5 which, as shown in Fig. 1, is the first of the heddle frames and is disposed immediately behind the lay 2, when said lay is in its back-center position above noted.

The heddle frame 5 is controlled by one of the cams on the common shaft by which the frames 6 to 10 inclusive are controlled, said frame being movable from a high to a low position and vice versa to carry the movable sections 55 of the fabric-spacing blades 50 up and down between the full and dotted line position shown in Fig. 1 as the warp sheds are formed for the introduction of the weft threads a¹—b¹ respectively.

As previously noted, when the lay moves to its front-center position to beat up a newly inserted weft thread and the pin roll 16 advances to take up the fabric to the desired extent, the blades 50, 70 being interwoven with the double pile fabric between the two base fabrics A and B, advance a corresponding distance with the fabric and in order to strip the fabric off the ends 60 of the blades 50, these blades are moved rearwardly, 75 after each beat up movement of the lay, a dis-

tance equal to the distance the blades advanced with the fabric.

The retracting of the spacing blades 50 is effected at the time the lay moves into its back-center position and for that purpose the lay is 5 provided with a bar 80 which extends transversely across the loom behind the lay 2 and in front of the heddle frame 5 and which as said lay moves to its back-center position engages the forward edges of the heddle blades 72, which, as 10 the said lay approaches and moves into its extreme back-center position exerts a pull on the sections 55 of the spacing blades 50. The rearward pull of the sections 55 of the blades 50 imparts a corresponding rearward movement to the 15 blade 50 through the joint 56 and by which the fabrics A and B are delivered over the forward ends 60 of the blades 50.

In order to produce the necessary tension on the warp threads a, b and c, the peripheral faces 20 of the tensioning drums 31, 32 and 33 are roughened to grip the threads more securely. In the present instance these rolls are spirally wrapped with strips of abrasive material, such as sandpaper, as indicated at 90 in Fig. 6. The 25 abrasive material, by reason of its rough character, retains a firm grip on said warp threads and prevents relative slippage between the warp threads and the surfaces of the tensioning drums.

As the fabric is woven and taken up by the 30 pin roll 16, the warp threads a, b and c are intermittently pulled, which intermittently revolves the tensioning rolls 31, 32 and 33. Such rotation of the rolls 31, 32 and 33 is retarded, to apply the desired tension to the warp threads, by means 35 of brake bands 91, 92 and 93, which are respectively applied to peripheral surfaces of brake drums 94, 95 and 96. The brake drums 94, 95 and 96 are carried by the shafts 97, 98 and 99 which support the drums 31, 32 and 33 respectively. The shafts 97, 98 and 99 are mounted for rotation in and relative to fixed frames 100, 100 by which the tensioning rolls, the spacing bars 24, 25 and 26, and the guide rolls 27, 28 and 29 are supported in predetermined relation to each 45 other.

One end of the brake band 92 is permanently attached to the guide bar 28 around which the warp threads b pass, the opposite end of said brake band being adjustably secured at 101 to a 50 lever 102. The lever 102 is pivoted at 103 to a bracket 104 which in turn is adjustably mounted on the guide bar 28. The arm or lever 102 is provided with adjustable weights 105 by which the braking effort applied to the tension roll 32 55 may be regulated at will.

One end of the brake band 93 is permanently attached to the guide bar 29 over which the pile warps c pass. The opposite end of the brake band 93 is pivotally connected at 106 to one end 60 of a lever 107. The lever 107 is pivotally mounted at 108 to a bracket 109 which is adjustably mounted on the guide bar 29. The lever 107 is provided with a single weight 110 adjustable longitudinally of the arm 107 for regulating the 65 braking effort applied to the tensioning roll 33.

In order to prevent wrinkling of the under fabric A which apparently is caused by reason of this fabric assuming an arc of smaller radius than that assumed by the fabric B in passing 70 around the breast beam roller 13, it has been found necessary to apply a greater tension to the warp threads a, of which the groundwork of the fabric A is composed, than is necessary to be applied to the warp threads b, forming the 75

ground fabric B, and in order to apply the desired amount of tension to the warps *a* it has been found necessary to increase the diameter of the tensioning roll 31, around which the threads *a* pass, over the diameter of the roll 32 for the threads *b*, in order to grip each thread *a* throughout a greater portion of its length than is required in the case of the threads *b*, in order to withstand the increased tension without slipping on the roll 31. A relatively different form of braking mechanism has also been employed in connection with the tensioning of the threads *a*, said braking mechanism comprising, as shown particularly in Figs. 4, 5 and 6, a lever 111 having a depending transversely elongated lug 112 arranged to rock in a cradle surface 113 formed in the upper edge of a bracket 114 carried by the side frame 100 of the tensioning device. The lever 111 is provided with a pair of laterally spaced depending lugs 115 between which extends a rod 116 to which one end of the brake band 91 is secured. The opposite end of the brake band 91 is provided with a threaded shackle bolt 117 which passes through a slot 118 formed in one end of the lever 111. At the opposite sides of the slot 118, the end 119 of the lever 111 is provided with a series of teeth 120. The teeth 120 are adapted to receive a tooth 121 formed on each side of the plate 122 through which the shackle bolt 117 passes. Threaded onto the shackle bolt 117 is a nut 123 which is arranged to be screwed down against the plate 122 for effecting minute adjustment of the brake band 91. The opposite end 124 of the lever 111 supports suitable weight 125 which in rocking the lever 111 about its pivot 112 applies the necessary retarding force to the rotation of the tensioning roll 31.

At times, during the weaving of double pile fabric or, and especially, during the weaving of a heading between the ends of two lengths or strips of the fabric, wherein the pile-forming warps are floated beneath the lowermost of the two superposed base fabrics which at that time are being woven more or less as separate fabrics connected together only at the selvage edges thereof by the weft or filling thread woven first into one and then into the other of the base fabrics at alternate picks respectively, the fabric tends to wrinkle in the direction of the warps, i. e. the selvage edges tend to move inwardly toward each other and cause the fabric to become wrinkled therebetween. These wrinkles extend longitudinally of the fabric through the heading and, in some cases, for some distance into the pile section which is woven subsequent to the heading.

In order to overcome the above noted longitudinal wrinkling of the fabric, the loom is provided, between the guide bar 52 for the base fabric spacers 59 and the guide roll 13 over which the composite fabric C passes after weaving, with a spreading device 130.

The spreading device 130 comprises a plurality of peripherally toothed wheels which are spaced apart across the breast beam and disposed in positions to contact with the fabric. The spreader wheels are arranged in two series. The wheels of each series are disposed in substantially parallel planes with the planes of the wheels of the one series arranged at acute angles to the plane of the fabric and breast plate 1 and pointing toward one edge of the fabric, while the planes of the wheels of the other series are arranged at reversely corresponding acute angles

to the fabric and breast plate and point toward the opposite selvage so that the two series are in opposed relation to each other with the planes of the two series of wheels in divergent relation to the longitudinal center line of the fabric and to a vertical plane coincident with the longitudinal center line of the fabric, i. e. a line substantially equidistant from the oppositely disposed selvages of the fabric.

A valuable advantage of the above resides in the fact that in addition to keeping the fabric from wrinkling it permits the use of a lesser number of warp ends across the fabric to maintain a predetermined width to the fabric than can normally be used to produce a fabric of equal width, with a resulting saving in the cost of material to the manufacturer.

The double pile fabric is woven in a continuous strip which is made possible by the warp threads being drawn from individual packages, making it possible to replenish the warp threads at any time and in any numbers so that the knots made in tying the threads of new packages to the threads of depleted packages are distributed throughout the length of the continuous strip of fabric.

In order to remove the fabric from the loom the strip is cut transversely when the roll on the mandrel 20 is of a predetermined size containing a predetermined number of yards. In order to provide for such cutting and in order to facilitate the splitting operation, wherein the two strips of double woven fabric are split apart in a plane intermediate the planes of the two base fabrics, non-pile headings are made periodically in the continuous strip by dropping the pile warps below the lower base fabric and not weaving these threads into either of the base fabrics.

The dropping of the pile warps to non-weaving position during the weaving of a heading is accomplished by rendering inoperative the means by which the heddle frame which controls the pile warps is raised and lowered. In different looms this would be accomplished in different ways. In looms of the type to which the present case is directed rendering of the pile-lifting means ineffective is accomplished merely by holding a cam follower out of contact with a cam by which the pile warps are normally raised.

I claim:

1. In a loom of the kind described employing a group of warp threads for each of the upper and lower base fabrics of a double pile fabric and a group of pile warps for connecting said base fabrics, the combination of a tension roll for each group of warp threads, with the tension roll for the warps of the lower base fabric of relatively greater diameter than the rolls for the other groups of said warp threads as and for the purpose described.

2. In a loom of the kind described employing a group of warp threads for each of the upper and lower base fabrics of a double pile fabric and a group of pile warps for connecting said base fabrics, the combination of a tension roll for each group of warp threads, with the tension roll for the warps of the lower base fabric of relatively greater diameter than the rolls for the other groups of said warp threads, and guides for said threads disposed adjacent said rolls and arranged to guide said threads around substantially the full circumference of each roll to increase the grip areas of the rolls on the threads of each group respectively.

3. In a loom of the kind described employing

5 a group of warp threads for each of the upper and lower base fabrics of a double pile fabric and a group of pile warps for connecting said base fabrics, the combination of a tension roll for each group of warps threads, with the tension roll for the warps of the lower base fabric of rel-

atively greater diameter than the rolls for the other groups of said warp threads, and abrasive tape spirally wound on each roll with the abrasive face thereof outwardly to engage said threads respectively.

5

WILLIAM H. HALL, JR.
